US00D660967S

(12) **United States Design Patent**
Braido et al.

(10) **Patent No.:** **US D660,967 S**
(45) **Date of Patent:** ** *May 29, 2012

(54) **SURGICAL STENT**

(75) Inventors: **Peter Nicholas Braido**, Wyoming, MN (US); **Thomas Mark Benson**, Minneapolis, MN (US); **Aaron J. Chalekian**, Minneapolis, MN (US); **Yousef F. Alkhatib**, Edina, MN (US)

(73) Assignee: **St. Jude Medical, Inc.**, St. Paul, MN (US)

(*) Notice: This patent is subject to a terminal disclaimer.

(**) Term: **14 Years**

(21) Appl. No.: **29/375,253**

(22) Filed: **Sep. 20, 2010**

(51) **LOC (9) Cl.** 24-02

(52) **U.S. Cl.** **D24/155**

(58) **Field of Classification Search** D24/155, D24/156, 133, 152, 154, 135, 141, 144-146, D24/151; 606/194, 198; 623/23.54, 23.7, 623/1.11, 1.15, 1.16, 903, 1.29; 604/1.02, 604/103.02; 128/204.18

See application file for complete search history.

CLAIM

The ornamental design for a surgical stent, as shown and described.

DESCRIPTION

FIG. 1 is a top perspective view of a surgical stent showing my new design;

FIG. 2 is a front side elevational view thereof;

FIG. 3 is a rear side elevational view thereof;

FIG. 4 is a right side elevational view thereof, the left side elevational view being a mirror image of the right side;

FIG. 5 is a top plan view thereof;

FIG. 6 is a bottom plan view thereof;

FIG. 7 is an enlarged perspective view of a feature thereof shown in FIG. 2;

FIG. 8 is an enlarged perspective view of a feature thereof shown in FIG. 2;

FIG. 9 is an enlarged perspective view of a feature thereof shown in FIG. 2;

FIG. 10 is an enlarged perspective view of a feature thereof shown in FIG. 2;

FIG. 11 is an enlarged perspective view of a feature thereof shown in FIG. 2;

FIG. 12 is an enlarged perspective view of a feature thereof shown in FIG. 2; and,

FIG. 13 is an enlarged perspective view of a feature thereof shown in FIG. 2.
